UNITED STATES PATENT OFFICE.

FRANZ TRINKS, OF BRUNSWICK, GERMANY.

CARRYING MECHANISM FOR CALCULATING-MACHINES.

1,098,193.

Specification of Letters Patent. Patented May 26, 1914.

Application filed October 30, 1913. Serial No. 798,305.

To all whom it may concern:

Be it known that I, FRANZ TRINKS, manufacturer, citizen of the Duchy of Brunswick, Empire of Germany, residing at Brunswick, Germany, have invented certain new and useful Improvements in Carrying Mechanisms for Calculating-Machines, of which the following is a specification.

My invention relates to improvements in carrying mechanisms for calculating machines, and more particularly in carrying mechanisms in which the carrying operation is performed by means of disks located in front of the numeral wheels and taking part in the rotation of the latter. If in such mechanisms a numeral wheel passes from its "nine" position to its "zero" position, or vice versa, it shifts abutment members into the path of coöperating teeth provided on the disk, whereby the numeral wheel of the next higher order is shifted forward or backward a distance corresponding to one digit. Carrying mechanisms of this type are suitable for use in combination with the main registering mechanism as well as with the revolutions counting mechanism of calculating machines of different constructions.

My invention consists in the matters described hereinafter and particularly pointed out in the appended claims.

For the purpose of explaining the invention several examples embodying the same have been shown in the accompanying drawings, in which the same letters of reference have been used in all the views to indicate corresponding parts.

In said drawings—Figure 1, is a front view of a calculating machine with the cover of the casing partly removed and partly in section, Fig. 2, is a cross-section taken on the line 2—2 of Fig. 1, Fig. 3, is an enlarged end view, seen from the left in Fig. 5, of a part of the main registering mechanism of the machine shown in Figs. 1 and 2, Fig. 4, is a similar end view of the part shown in Fig. 3, seen from the right in Fig. 5, Fig. 5, is a front view of the said part, Fig. 6, is an end view seen from the left in Fig. 7 and partly in section, showing a modification of the invention, Fig. 7, is a front view of Fig. 6, Fig. 8, shows a further modification, and Figs. 9, 10, and 11, are end views of further modifications.

Referring now more particularly to Figs.

1 to 5 of the drawings, a shaft 24 which is 55 adapted to be rotated by a crank 23 carries a plurality of setting disks 25 which are provided with radially shiftable teeth 26 adapted to be shifted into or out of operative positions by cam disks 27, one cam disk 60 being provided for each of the setting disks. The cam disks are provided with finger pieces 28 projecting through slots 29 of the cover 29 of the casing of the machine. In front of the disks 25 and 27 which constitute the setting mechanism a carriage 30 is mounted in suitable guides 32 in the base plate 31 of the machine, which carriage is adapted to be shifted in a direction parallel with shaft 24 of the setting mechanism. On 70 the carriage a shaft 10 is mounted which is parallel with the shaft 24 and carries a plurality of numeral wheels 1 provided about their circumferences with the characters from "1" to "9" and the "zero" sign and 75 constituting the registering mechanism. Each of the disks 1 is equipped with spur gears 12 adapted to be engaged when turning the crank 23 by the teeth 26 of the co-operating setting disk 25, so that the numeral wheels 1 are turned forward or backward distances corresponding to the numbers set up on the setting disks.

On the carriage 30 a revolutions counting mechanism 11 is mounted coaxially of the 85 registering mechanism 1. The said revolutions counting mechanism is adapted to be operated once for each operation of the crank, by means of a single tooth wheel 33, which turns the said revolutions counting 90 mechanism one value forward or backward.

The mechanisms 1 and 11 are equipped with resetting devices of any known or preferred construction. To show what may be done, the shafts 10 and 34 are provided with 95 wing nuts 35 and 36, and with pins 10' and 34'. When turning the wing nuts the pins 10' and 34' engage noses 1" and 11" in the numeral wheels 1 and 11 respectively and return the same into their zero positions.

As is shown most clearly in Figs. 3 to 5, each of the numeral wheels 1 is provided at its left side with a slide 2 which is adapted to be shifted against the action of a spring 4 by an abutment such as a pressure roller 3 located adjacent to the wheel 1, so that a finger 5 which projects from the inner end of the slide 2 to the left is moved toward the

periphery of the wheel. The finger 5 is so long that it is adapted to transmit the movement imparted thereto by the abutment 3 to the adjacent numeral wheel, as is shown 5 in Fig. 5. At the right hand side each numeral wheel 1 is equipped with ten teeth 6 which are adapted to be projected radially, and which are uniformly distributed according to the characters provided about the circumferences of the numeral wheels. The parts are so arranged, that in the regular 10 positions of the numeral wheels 1 each finger 5 can engage the enlarged inner end of a tooth 6 of the adjacent wheel, when it is shifted outward by the coöperating abutment 3. The ten teeth 6 are held in either one of their end positions by a spring actuated locking ring 7 which engages in notches 15 8 or 9 of the teeth 6, as is shown in Figs. 4 and 5. When a tooth 6 is shifted beyond the circumference of the numeral wheel 1, it projects into the path of a tooth 37 which is provided on a disk 38 disposed in the same 20 plane with the numeral wheel and taking part in the rotation of the shaft 24 of the setting mechanism. The tooth 37 engages the projected tooth 6 and advances the corresponding numeral wheel 1 a distance corresponding to one digit. At the end of the 25 shifting operation the projected tooth 6 is engaged by a stationary cam 17 provided at a suitable part of the machine and adapted to force the said tooth backward and away from the circumference of the numeral 30 wheel 1. The said cam is provided with two operative faces according to the two directions of rotation of the numeral wheel 1, as is shown in Fig. 2. Each of the disks 38 is provided with two teeth 37 corresponding to 35 the two directions of the revolution of the shaft 24 (Fig. 2). As is shown in Fig. 1, in all the disks 38 the teeth 37 which are operative for the same direction of rotation of the crank shaft are distributed on the disks according to a helical line, so that they are 40 successively thrown into operation according to the successive carrying operations.

In the construction shown in Figs. 6 and 5 7 rocking teeth are provided instead of the radially shiftable teeth shown in Figs. 1 to 5. At the right side of the numeral wheels 1' ten teeth 14 are provided which have rocking supports on pins 13 and are locked in their end positions by spring actuated 55 pins 18. When shifting one of the laterally projecting fingers 5' the corresponding tooth 14 is rocked upward, the finger 5' acting on a finger 16 of the tooth. The carrying operation is the same as has been described with 60 reference to Figs. 1 to 5 by means of teeth 37' provided on disks 38'. For returning the teeth into inoperative positions cams 2 are provided the construction and operation of which are similar to those of the cams 17 65 shown in Figs. 1 to 5.

Instead of the special disks 38 and 38' shown in Figs. 5 and 7 the well known setting disks 25 may be used for performing the carrying operation. In this case the teeth 37, 37' are mounted for instance on the 70 said disks 25 themselves. This construction will readily be understood without illustration. Furthermore in my improved carrying mechanism the well known rockable carrying teeth on the setting disks 25 may be used in their rocked positions or in their 75 inoperative positions (see for example teeth 67' of the machine shown in United States Letters Patent No. 1,040,059 granted to me October 1, 1912). In order to have a reliable 80 operation I prefer to lock the said teeth during the carrying operation in their rocked positions. As shown in Fig. 8 where the well known carrying teeth 67' perform the carrying operation in their rocked positions by acting on teeth 6', this locking may be effected by cam faces 39. If desired instead of the slide 2 a rocking lever may be provided.

Preferably the cam faces 17 are beveled 90 at both sides, as is shown in Figs. 2 and 4, so that the teeth 6 are forced backward also in such cases in which they are shifted outward at other places by reason of irregular 95 operation of the locking mechanism. Such constructions are also shown in Figs. 9 and 10. If at any improper time a tooth is shifted beyond the circumference of the disk, it is returned into inoperative position before it is brought into position for performing a 100 carrying operation. In the construction shown in Fig. 9 each of the cams 17' is also provided with a cam face 17'' at the side which is opposed to the point at which the teeth 6' are struck by the tooth 37, and the 105 said cam faces 17'' are so shaped, that they force any tooth 6' backward and into the numeral wheel 1'', which might accidentally be projected beyond the periphery of the numeral wheel 1'' and approaches the point x 110 and this is done before the tooth arrives at the point x. Each of the cams 17' is stationary relatively to the numeral wheel and its parts are located symmetrically of a diameter of the said wheel. Preferably the cams 115 17' are arranged in such a way, that when a tooth 6' is being shifted outward the points y at which the cam faces 17'' and 17''' intersect are located adjacent to the teeth 6' which adjoins the said tooth 6' being shifted. In this case the said points lock the adjoining teeth against being simultaneously projected.

In the example shown in Fig. 10 the cams which act in both directions are constructed 125 in the form of levers 21 having rocking supports at 20. The heads 21' of the said levers are beveled at both sides and their points 21'' are directed toward the tooth 37'' performing the shifting operation, so that the 130

said heads can be shifted by the said tooth to the side against the action of the springs 22, whether the crank of the machine is being turned forward or backward. The levers 21 are constructed in such a way, that when they are being shifted to the side as described their heads 21' move radially toward the numeral wheel 1''' and strike in the manner of hammers on the projecting tooth 6''' and force the same backward and into its disk.

In the construction shown in Figs. 1 to 5 much difficulty is met with when providing means for locking the radially shiftable teeth in their end or operative and inoperative positions, because by reason of the small size of the numeral wheels very little space is available for the locking means. In the construction shown in Fig. 9 this difficulty is avoided by providing a locking ring 7' which is common to all the teeth 6', and which is forced by spring action into engagement with either one of notches 8' and 9' of the teeth 6', so as to lock the teeth in their end positions. Such a ring requires a minimum of space, and it may be disposed at the side of the numeral wheel, where it is easily accessible. In this construction the ring 7' has a rocking movement about the axis of the numeral wheel 1'', and it is formed at its front face with beveled noses 7'' adapted to engage in beveled notches 8' or 9' of the teeth 6'. By means of two springs 19 which are diametrically opposed to each other the ring is forced into engagement with either one of the notches. If a tooth 6' is forced outward or inward respectively by a member, such as finger 5 or 5' shown in Figs. 5 and 7 engaging at the rear of the inner end 6'' of the tooth, or a cam 17' located adjacent to the numeral wheel, the ring 7' yields against the pressure of the springs 19 and permits its nose 7'' to disengage the notch of the tooth 6'. In this operation the ring 7' rocks about the axis of the numeral wheel, while being guided by pins 41 secured to the numeral wheel, and it returns into the position shown in the figure, when the tooth 6' arrives in its new end position. While the ring 7' is being rocked all the teeth 6' are released. If one of the teeth which are remote from the point α should be shifted beyond the circumference of the numeral wheel, no harm is done, because the cams 17' which are operative in both directions force the said tooth backward and into the disk before it reaches its operative position at point α . If desired special means may be provided for preventing the teeth from being accidentally shifted. To show what may be done a covering plate 42 is provided which closely encircles the numeral wheel 1''', and is open at the operative part α' , as is illustrated in Fig. 11. The breadth of the plate 42 is such, that neither the shift-

able slide 2' nor the characters from 0 to 9 provided about the circumference are covered.

I claim herein as my invention:

1. In a carrying mechanism, the combination with at least two numeral wheels, and mechanism for setting up numbers on said numeral wheels, of shiftable members on the numeral wheel of higher order, a shifting member on the numeral wheel of lower order adapted to shift either one of said shiftable members into operative position, at least one movable carrying member adapted to engage a shiftable member when shifted in operative position and thereby to shift the numeral wheel carrying the shiftable members, and means to return the shiftable member into inoperative position.

2. In a carrying mechanism, the combination with at least two numeral wheels, and mechanism for setting up numbers on said numeral wheels, of shiftable members on the numeral wheel of higher order the number of which corresponds to the number of values represented by the numeral wheel, a shifting member on the numeral wheel of lower order adapted to shift either one of said shiftable members into operative position, at least one movable carrying member adapted to engage a shiftable member when shifted in operative position and thereby to shift the numeral wheel carrying the shiftable members, and means to return the shiftable member into inoperative position.

3. In a carrying mechanism, the combination with at least two numeral wheels, and mechanism for setting up numbers on said numeral wheels, of shiftable members on the numeral wheel of higher order, a shifting member on the numeral wheel of lower order adapted to shift any one of said shiftable members into operative position, stationary operating means adapted to operate the shifting member, at least one movable carrying member adapted to engage a shiftable member, when shifted into operative position and thereby to shift the numeral wheel carrying the shiftable members, and means to return the shiftable member into inoperative position.

4. In a carrying mechanism, the combination with at least two numeral wheels, and mechanism for setting up numbers on said numeral wheels, of shiftable members on the numeral wheel of higher order, a shifting member on the numeral wheel of lower order adapted to shift any one of said shiftable members into operative position, at least one movable carrying member adapted to engage a shiftable member when shifted into operative position and thereby to shift the numeral wheel carrying the shiftable members, and cams provided for returning the shiftable member which has been shifted by the shifting member into

70

130

inoperative position, said cams being provided with cam faces for returning the members which have accidentally been shifted into operative position before such 5 members arrive in position for engagement by the carrying member.

5. In a carrying mechanism, the combination with at least two numeral wheels, and mechanism for setting up numbers on 10 said numeral wheels, of shiftable members on the numeral wheel of higher order, a shifting member on the numeral wheel of lower order adapted to shift any one of said shiftable members into operative position, 15 at least one movable carrying member adapted to engage a shiftable member when shifted into operative position and thereby to shift the numeral wheel carrying the shiftable members, and at least one cam constructed 20 in the form of a rocking hammer adapted to be rocked by said movable carrying member and when rocked to strike the shiftable member which has been shifted into operative position and thereby to return the said member into inoperative position.

6. In a carrying mechanism, the combination with at least two numeral wheels, and mechanism for setting up numbers on said 30 numeral wheels, of shiftable members on the numeral wheel of higher order, a shifting member on the numeral wheel of lower order adapted to shift either one of said shiftable members into operative position, at least one 35 movable carrying member adapted to engage a shiftable member when shifted into operative position and thereby to shift the numeral wheel carrying the shiftable members, and two cams in the form of rocking 40 hammers adapted to be rocked by said movable carrying member and when rocked to strike the shiftable member which has been shifted into operative position and thereby to re-

turn the said member into inoperative position.

7. In a carrying mechanism, the combination with at least two numeral wheels, and mechanism for setting up numbers on said numeral wheels, of shiftable members on the numeral wheel of higher order, a shift- 45 ing member on the numeral wheel of lower order adapted to shift any one of said shift- 50 able members into operative position, yield- 55 ing means for locking said shiftable mem- bers in their end positions, at least one mov- able carrying member adapted to engage a shiftable member when shifted into opera- 60 tive position and thereby to shift the nu- 65 meral wheel carrying the shiftable members, and means to return the shiftable member 65 into inoperative position.

8. In a carrying mechanism, the combination with at least two numeral wheels, and mechanism for setting up numbers on said numeral wheels, of shiftable members on the numeral wheel of higher order, a shifting member on the numeral wheel of lower order adapted to shift either one of said shiftable members into operative position, a yielding 70 ring common to all the shiftable members 70 and adapted to lock the shiftable members in their end positions, at least one movable carrying member adapted to engage a shift- 75 able member when shifted into operative position and thereby to shift the numeral 75 wheel carrying the shiftable members, and means to return the shiftable member into inoperative position.

In testimony whereof I have hereunto set my hand in presence of two subscrib- 80 ing witnesses.
